UNITED STATES PATENT OFFICE

168,725

HEADREST

John T. Armbruster, Niagara Falls, N. Y., assignor
to American Optical Company, Southbridge,
Mass., a voluntary association of Massachusetts

Application June 22, 1951, Serial No. 15,638

Term of patent 14 years

(Cl. D15—3)

To all whom it may concern:

Be it known that I, John T. Armbruster, a citizen of the United States of America, residing at Niagara Falls, in the county of Niagara and State of New York, have invented a new, original, and ornamental Design for a Headrest, of which the following is a specification, reference being made to the accompanying drawing, forming a part thereof.

Fig. 1 is a front elevational view of a headrest showing my new design;

Fig. 2 is a side elevational view thereof; and

Figs. 3, 4, 5, 6 and 7 are cross-sectional views taken through the respective arms of the headrest to show the characteristic shapes thereof.

The characteristic features of my design are shown in full lines in the drawing.

I claim:

The ornamental design for a headrest, substantially as shown and described.

JOHN T. ARMBRUSTER.
